(57) CLAIM

I claim the ornamental design for a footwear, as shown and described.

DESCRIPTION

FIG. 1 is a perspective side view showing my new design; FIG. 2 is a right elevation side view thereof; FIG. 3 is a left elevation side view thereof; FIG. 4 is a front elevation view thereof; FIG. 5 is a rear elevation view thereof; FIG. 6 is a top view thereof; and, FIG. 7 is bottom view thereof.

In the drawings, the broken lines are for the purpose of illustrating environment only and form no part of the claimed design.
